SERVING DISH STAND

Richard B. Andrus and James R. Washburn,
Boulder, Colo.

Application February 1, 1954, Serial No. 28,760

Term of patent 3½ years

(Cl. D44—10)

We claim:

The ornamental design for a serving dish stand, as shown and described.
